CLEAR LIQUID SOLUBILIZED LANOLIN COMPOSITIONS

Ling Wei, North Bergen, N.J., assignor to Colgate-Palmolive Company, New York, N.Y., a corporation of Delaware

No Drawing. Application July 5, 1957
Serial No. 669,967

16 Claims. (Cl. 167—90)

The present invention relates to the solubilization of lanolin by a higher aliphatic amide compound and, more particularly, to clear aqueous compositions comprising solubilized lanolin and process of preparing the same, as hereinafter described and claimed.

Lanolin is a waxy material which has been employed extensively in cosmetic preparations and the like because of its emollient and emulsifying characteristics. It is insoluble in water and therefore has been suspended usually in aqueous-containing preparations, particularly in the manufacture of various creams, pastes, oils and emulsions. Heretofore, preparations containing lanolin dissolved or dispersed in water so as to form a clear solution have not been made as articles of commerce in view of the water-insolubility and other unique properties of lanolin.

In accordance with the present invention, it has been discovered that lanolin can be rendered water-soluble by combination with a higher aliphatic amide compound as a solubilizing agent. More particularly, the present invention relates to a clear aqueous composition comprising about 0.05 to 5% by weight of lanolin and a minor proportion of at least 0.25% by weight of a higher fatty acid alkylolamide, the ratio of said amide to lanolin being at least 1:1 by weight, and these ingredients being dissolved in an aqueous liquid solvent medium having a water content of at least about 50% by weight of the total composition. A preferred embodiment is a clear transparent aqueous composition comprising about 0.05 to 5%, preferably up to 1%, of lanolin, about 0.25 to 20%, of said amide compound, the ratio of said amide to lanolin from about 2:1 to 100:1 and a minor proportion of a water-soluble organic surface active agent in an aqueous medium. Various other preferred embodiments will be apparent in the following description.

The lanolin is a water-insoluble purified fat-like substance from sheep wool whose composition is not fully known at this time. In general, it comprises at least about 90% of esters derived from a variety of higher alcohols and higher fatty acids. The alcoholic portions of the esters are composed of sterols, triterpenoid alcohols and mixed aliphatic alcohols whereas the higher fatty acids are a complex mixture of normal, hydroxy, iso and anteiso acids. The lanolin contains usually minor amounts of free complex alcohols, acids and hydrocarbons. The total cholesterol content will be usually at least about 15% by weight. The lanolin is available in a variety of purified grades, such as the U.S.P. grade, which may be employed in the present invention. Other suitable grades such as fractionated lanolin in which various materials such as free alcohols or the like are removed by distillation or other suitable means may be employed also. A typical material is the liquid fraction from lanolin composed of liquid lanolin esters having a cholesterol content of at least about 15%. Accordingly, the term "lanolin" as used in the specification and claims is intended to cover water-insoluble lanolin and water-

2

insoluble fractionated lanolin containing the lanolin esters.

The amide compound used as a solubilizing agent is a higher aliphatic alkylolamide. Such materials are known and have been employed in cosmetic and detergent compositions as thickeners, foam modifying agents and the like. In the instant invention, the acyl radical will be usually a higher fatty acyl radical of about 8 to 18 carbon atoms, preferably about 10 to 14 carbons, and each alkylol radical will be usually a lower alkylol group, such as up to five carbon atoms, preferably 2 to 3 carbons. The alkylol groups may be mono- or polyhydroxy alkyl and may be substituted by inert substituents.

It is preferred to employ the higher fatty acid dialkylolamides, such as lauroyl diethanolamide, myristoyl diethanolamide, coconut fatty acid diethanolamide, oleyl diethanolamide, stearoyl diethanolamide, lauroyl diisopropanolamide and the like because of the greater solubility of these materials as compared to the monoalkylolamides usually.

These dialkylolamides may be prepared in any suitable manner and utilized in pure or commercial grades in the present invention. It is preferred to use a water-soluble liquid dialkylolamide condensation product of a higher fatty acylating substance and a lower dialkylolamide (e.g. diethanolamine) in about a 1:2 ratio. Such product has usually a dialkylolamide content of at least about 60% and has chemically and/or physically associated with the dialkylolamide a number of other by-product (including unreacted) materials such as minor proportions of soap e.g. 5-25%, free alkylolamine e.g. 1-10% ester-amide, etc. A typical suitable reaction mixture cited for illustrative purposes and resulting from the condensation of commercially distilled lauric acid or coconut fatty acids and commercial diethanolamine contains the following components on a solids basis: about 65% diethanolamide, about 10% diethanolamine soap, about 5% free alkylolamine, minor amounts of various by-products such as possibly ester-amide, piperazine derivatives, etc. The presence of small amounts of such materials in admixture with the dialkylolamide is believed to aid in the water-solubility and liquidity of the dialkylolamide reaction product. The presence of the soap and free dialkylolamine acts as a solubilizing agent for the amide in water and clear, transparent or translucent solutions may be obtained thereby. Similar dialkylolamides of greater purity such as at least about 90% may be produced by the reaction of about a 1:1 ratio of the reactants, such as from the reaction of higher fatty acid methyl esters with diethanolamine and such products are substantially free from soap and free alkylolamine and exhibit less solubility in water.

The corresponding higher fatty acid monoalkylolamides may be utilized also, such as the fatty acid monoethanolamides, n-propanolamides and isopropanolamides. Suitable examples are lauroyl monoethanolamide and isopropanolamide, coconut fatty acid monoethanolamide and isopropanolamide, oleyl monoethanolamide and isopropanolamide, and the like.

Depending upon the specific character of the fatty acyl radical and the alkylolamine and the conditions of the condensation reactions, the alkylolamide products vary in physical form from liquids to pastes and waxes and may be water-soluble, water-dispersible or relatively insoluble.

It is a basic aspect of the present invention that the preparation of a clear aqueous solution comprising solubilized lanolin and alkylolamide embodies a particular sequence of operations dependent upon the character of the ingredients. The order of addition is critical and controls the final character of the product and the obtention of the lanolin in solution. The term "soluble," "solu-

"bilized" or equivalent wording with respect to lanolin and similar references includes the formation of an aqueous solution or dispersion containing the lanolin dissolved colloidally or dispersed therein so that the lanolin is not detectable by ordinary visual examination at room temperature.

The initial concentrate or mixture is prepared by the admixture of the lanolin and alkylolamide with stirring to form a smooth, homogeneous mixture. The temperature of admixture is not critical and the mixing may be done at room temperature or at elevated temperatures such as up to about 180° F. if desired. The lanolin may be added in solid or molten form to the alkylolamide. In the event that the alkylolamide is solid or is not sufficiently liquid at room temperature, it may be heated moderately to obtain a molten or liquid state and permit uniform and ready admixture with the lanolin. The lanolin appears to be dissolved or solubilized by the alkylolamide material and the resulting concentrate may be a transparent or translucent fluid or a homogeneous waxy solid, depending upon the physical state of the alkylolamide. The ingredients should be admixed in proportions to obtain a concentrate of the lanolin in the alkylolamide as a solvent or dispersion medium. In general, the ratio or proportions will be from 0.05 to 5 parts of the lanolin to 0.25 to 50 parts of the dialkylolamide, the amount of amide being sufficient to solubilize the same. The ratio of amide to lanolin will be usually at least about 1:1, preferably about 2:1 to 100:1 by weight.

This initial mixing operation to form a homogeneous concentrate is conducted under substantially anhydrous conditions by which is meant the absence of such proportions of water which would precipitate or substantially adversely affect the solubilization of the lanolin. It has been found that if the lanolin is added to an aqueous medium containing significant or substantial amounts of water, followed by the alkylolamide, there does not result a uniform solution or dispersion but rather a two-phase system with the lanolin in particle form either floating on the aqueous medium or forming a precipitate. On the other hand, the alkylolamide medium which is mixed with the lanolin in accordance with the present invention may contain varying amounts of water provided that it does not substantially adversely affect the solubilization of the lanolin. While the permissible amounts of water will vary with the character and proportions of the ingredients, in general any water present during the initial admixture should be a minor amount, such as less than about 30%, preferably less than 20%, provided that it does not substantially interfere with the formation of the desired product.

It is a feature of the present invention that the mixture of lanolin and alkylolamide is combined with a solubilizing or coupling agent which enables the alkylolamide to be water-soluble or dispersible in an aqueous system sufficiently to form a clear solution. Such solubilizing agents for the amide are known and include the soaps and free amine previously described which are in some alkylolamide reaction products. Any suitable surface active agent may be employed since the desired solubilization effect is an observable phenomenon and readily determinable.

In general, it is preferred that the lanolin and alkylolamide are combined with a water-soluble detergents material. Either ionic or non-ionic detergents may be employed but optimum effects are obtained with the water-soluble anionic soaps and synthetic detergents (including suitable mixtures thereof). Included therein are the water-soluble anionic sulfate and sulfonate detergents such as the higher alkyl aryl sulfonates, the higher alkyl sulfates, the sulfuric acid esters of polyhydric alcohols incompletely esterified with higher fatty acids, the higher fatty acid esters of hydroxy propane sulfonic acid, the higher fatty acid esters of low molecular weight alkylol

sulfonic acids, the higher fatty acid alkylolamide sulfates, the higher fatty acid amides of amino alkyl sulfonic acids, etc. Other anionic synthetic detergents are the higher fatty acid amides of amino carboxylic acids.

6 Examples of these various detergents are dodecyl benzene sulfonate, propylene tetramer benzene sulfonate, ketyl benzene sulfonate, higher fatty acid monoglyceride monosulfate, lauryl sulfate, coconut fatty alcohol sulfate, coconut fatty acid ester of ethanolamide sulfate, lauric acid amide of taurine, oleic acid ester of isethionic acid, lauric acid amide of sarcosine and the like. The water-soluble soaps of higher fatty acids may be employed also. Such soaps are derived from the natural or synthetic fats, oils, waxes. They comprise the water-soluble salts of coconut oil, corn oil, hydrogenated coconut oil, lauric acid, myristic acid, palm oil, olive oil, palm kernel oil, etc.

10 These various anionic detergents are used in the form of their water-soluble salts such as the alkali metal and ammonium (including substituted ammonium) salts. Examples are the sodium, potassium, lithium, ammonium, and alkylolamine salts. It is preferred to employ an alkylolamine salt at least in part in the product in view of the greater solubility of such salts in water usually.

15 20 Examples of alkylolamine salts are the mono-, di- and triethanolamine, mono- and diisopropanolamine salts, including mixtures thereof.

25 These various anionic detergents are used in the form of their water-soluble salts such as the alkali metal and ammonium (including substituted ammonium) salts. Examples are the sodium, potassium, lithium, ammonium, and alkylolamine salts. It is preferred to employ an alkylolamine salt at least in part in the product in view of the greater solubility of such salts in water usually.

30 35 Examples of alkylolamine salts are the mono-, di- and triethanolamine, mono- and diisopropanolamine salts, including mixtures thereof.

40 45 There may be employed also non-ionic detergents or surface-active agents. These agents are known in the art and include the polyoxyethylene ethers of alkyl aromatic hydroxy compounds (e.g. polyoxyalkylene condensates of higher alkyl phenols), polyoxyethylene ethers of higher aliphatic alcohols, polyoxyalkylene esters of higher fatty acids, suitable alkylolamide condensates, etc.

50 55 The above surface-active agents may be fixed with the lanolin and the dialkylolamide as part of the initial stage of preparation of the aqueous product. In such mixture, the added detergent appears to aid in the solubilization of the lanolin in the alkylolamide. A small amount of water is used usually with the added detergent provided it is insufficient to produce insolubilization of the lanolin since it is more convenient to add the detergent in the form of an aqueous solution. Alternatively, these detergents may be incorporated in the product as a subsequent or separate operation. The added detergents may be added to an already formed mixture of lanolin and alkylolamide with sufficient stirring to form a smooth, homogeneous product either before or after the addition of water as a final solvent medium.

60 65 The proportion of such added detergents or surface-active agent is variable and sufficient to solubilize the amide. In general, the amount will be from about 0.25 to 50 parts by weight. In the manufacture of shampoos and similar preparations, it is preferred to incorporate a foaming water-soluble organic detergent in an amount from about 5 to 50 parts, most preferably about 10 to 30 parts by weight of the final product.

70 75 After preparation of the initial concentrate with or without the added surface-active agent, any desired proportion of water may be incorporated in the presence of the amide solubilizer to form a composition having water as the solvent medium in which the lanolin is solubilized by the alkylolamide. The materials are stirred until a homogeneous solution is obtained. The mixing temperature is not critical and the same conditions may be employed as in the initial stage of the process. In general, it is desired that the amount of water be at least about 50% by weight of the final solution, and preferably at least about 60% by weight. The resulting composition may exhibit some cloudiness or haziness, which is primarily due to impurities in the lanolin wax. These impurities may be removed by any technique suitable for solid-liquid phase separation. It has been found that the cloudiness may be removed easily by a filtration step wherein the liquid is filtered on a filter cloth or press.

The resulting filtrate is a clear, sparkling transparent liquid having the lanolin in solution. The presence and proportion of lanolin in the filtrate may be determined by suitable analysis such as by determination of the cholesterol content by the digitoxin precipitation method.

The composition containing the lanolin and alkylolamide, whether the initial concentrate with or without an amide solubilizing agent and with or without the subsequent addition of water as described, may be employed in the preparation of any suitable cosmetic (or pharmaceutical or detergents) products or may be employed directly in any cosmetic use by the consumer. The term "cosmetic preparation" or the like as used herein refers to a preparation which is applied to or contacts the hair, skin or any other portions of the body whether such contact is a primary or incidental function of the composition in the course of its intended or designed uses. Examples of such products are deodorants, anti-bacterial compositions, shaving preparations, shampoos, hair preparations, rinses, washing, cleansing and detergents compositions including dishwashing preparations, lotions and the like where the presence of lanolin is desired.

Various materials may be added to any of the compositions provided they are selected so as to be compatible with the composition. Minor amounts of sequestering agents such as water-soluble phosphate compounds (e.g. monosodium phosphate) may be added to the composition. Preservatives such as formalin may be added similarly in small amounts. Other ingredients such as coloring materials, dyes, hair conditioning agents, antibacterial agents (e.g. hexachlorophene), perfume, and the like may be added in small amounts as desired.

The following specific examples are further illustrative of the nature of the present invention, but it is to be understood that the invention is not limited thereto. The amounts of the various ingredients are by weight unless otherwise indicated.

EXAMPLE I

Ingredients:	Parts
Lanolin	0.5
Coconut diethanolamide	5
Perfume	0.4

The coconut diethanolamide is a water-soluble liquid reaction product prepared by reacting coconut fatty acids with diethanolamine in about a 1:2 ratio to obtain a condensate comprising about 65% coconut diethanolamide, about 15% soap, about 5% alkylolamine and minor amounts of by-products.

The above ingredients are mixed at room temperature by the slow addition of the lanolin (U.S.P.), followed by the perfume, to the liquid diethanolamide condensate with stirring to form a clear, translucent viscous liquid product.

The solution of Example I is added to about 90 parts of water with stirring at room temperature to form a homogeneous aqueous solution which is clear and transparent and exhibits no separation at room temperature over long periods of time.

EXAMPLE II

A clear, transparent liquid shampoo is prepared as follows:

Part I

Parts

Lanolin	0.5
Liquid coconut diethanolamide	5.0
Perfume	0.4

Sodium lauryl sulfate	9.0
Triethanolamine dodecyl benzene sulfonate	8.0
Potassium higher fatty acid soap	2.5

Part III

Water	73.9
Monosodium phosphate	0.5
Preservative	0.2

100.0

The ingredients of Part I are blended thoroughly at room temperature for about 30 minutes. The ingredients of Part II are each dissolved in a small amount of water of Part III and are added successively to the Part I mixture with sufficient stirring for about 30 minutes to form a homogeneous liquid mixture. The remainder of the water, the phosphate and preservative (formalin) of Part III are added to the mixture with stirring for about 90 minutes. The mixture is filtered on a canvas filter cloth.

The resulting product is a clear transparent solution which is extremely stable at room temperature. The lanolin content of the solution is about 0.5% as shown by cholesterol content determined by the digitoxin precipitation method. In use as a liquid shampoo, the product develops a stable foam and improves the manageability of the hair.

EXAMPLE III

The procedure of Example II is repeated using an amber-colored fluid fraction of lanolin composed of the liquid lanolin esters and has a cholesterol content of 15 to 17%. The final product is a clear, transparent stable solution suitable for use as a shampoo.

EXAMPLE IV

The procedure of Example II is repeated with the same ingredients except that Part I included the lanolin, the diethanolamide condensate and, in addition, the triethanolamine dodecyl benzene sulfonate of Part II dissolved in about 5 parts water. The perfume is added with the remainder of the water in Part III. After the filtration as the final processing step, the product is a clear and sparkling solution which is stable to separation and is highly satisfactory in use as a shampoo.

EXAMPLES V-IX

The procedure of Example IV is repeated using in place of the coconut diethanolamide condensate of Part I the following substitute materials: (a) 1:1 mixture of lauric and myristic diethanolamide, (b) essentially pure coconut diethanolamide, (c) coconut monoethanolamide, (d) oleyl isopropanolamide, and (e) coconut isopropanolamide. Materials (a) and (c) are solids which are warmed sufficiently to liquefy them and the solid lanolin is added with stirring to form a uniform mixture. The remaining materials (b), (d) and (e) are liquids which are miscible with the lanolin.

After the addition of the ingredients of Part III and filtration, all of the final aqueous products are clear, transparent solutions and analysis shows the presence of the lanolin in solution.

EXAMPLE X

A concentrate of 0.5 part lanolin and 5 parts coconut diethanolamide condensate is prepared as in Example I. The resulting homogeneous liquid mixture is admixed with about 95 parts of a 23% aqueous solution of ammonium coconut fatty acid monoglyceride with stirring at room temperature. The product is filtered and the filtrate is a clear liquid containing the lanolin in solution. It has a variety of uses such as a shampoo, skin-cleansing liquid or bubble-bath composition.

EXAMPLE XI

A clear non-alcoholic cosmetic preparation suitable as an after-shave lotion is prepared as follows:

Ingredients:	Percent
Lanolin	0.5
Liquid coconut diethanolamide	5.0
Hexachlorophene	0.25
Perfume	0.1
Water	Q.S.

The lanolin, the diethanolamide condensate of Example I, hexachlorophene (2,2'-dihydroxy-3,5,6-3',5',6' hexachlorodiphenylmethane) and perfume are mixed at room temperature to form a homogeneous, translucent mixture. The product is mixed slowly with the water and filtered to obtain a sparkling clear stable solution.

EXAMPLE XII—HAIR DRESSING

A clear cosmetic preparation suitable as a hair dressing or a thick hand lotion is prepared as in Example XI according to the following formula:

Ingredients:	Percent
Lanolin	2.0
Liquid coconut diethanolamide	20.0
Hexachlorophene	1.0
Perfume	0.1
Water	Q.S.

Although the present invention has been described with reference to particular embodiments and examples, it will be apparent to those skilled in the art that variations and modifications of this invention can be made and that equivalents can be substituted therefor without departing from the principles and true spirit of the invention.

Having thus described the invention, what is claimed is:

1. A process for the preparation of a clear aqueous liquid cosmetic composition containing about 0.05 to 5% by weight of lanolin and at least about 50% by weight of water which comprises admixing said lanolin under substantially anhydrous conditions with a minor proportion of at least 0.25% by weight of a higher fatty acid alkylolamide having from 8 to 18 carbon atoms in the acyl radical and up to 5 carbon atoms in each alkylol group, the ratio of said alkylolamide to lanolin being at least 1:1 by weight and sufficient to solubilize the lanolin and form a homogeneous mixture, dissolving said mixture in a sufficient amount of said water as a liquid solvent medium and forming a clear aqueous liquid cosmetic composition.

2. A process in accordance with claim 1 wherein said mixture lanolin and higher fatty acid alkylolamide is dissolved in the water in the presence of a minor proportion of a water-soluble organic surface-active agent as a solubilizing agent for said alkylolamide, and recovering a clear aqueous liquid cosmetic composition.

3. A process for the preparation of a clear aqueous liquid shampoo composition containing about 0.05 to 5% by weight of lanolin, and at least about 60% by weight of water which comprises admixing said lanolin under substantially anhydrous conditions with a higher fatty acid alkylolamide having about 10 to 14 carbon atoms in the acyl radical and up to 3 carbon atoms in each alkylol group, the amount of said alkylolamide being about 0.25 to 20% by weight and the ratio of said alkylolamide to lanolin being from about 2:1 to 100:1 by weight and sufficient to solubilize the lanoline and form homogeneous mixture, dissolving said mixture in a sufficient amount of said water as a liquid solvent medium in the presence of about 10 to 30% by weight of a water-soluble organic anionic detergent, filtering the resulting mixture and recovering a clear aqueous shampoo composition.

4. A process in accordance with claim 3 which contains a higher fatty acid diethanolamide having 10 to 14 carbons in the acyl radical.

5. A process in accordance with claim 3 which contains a higher fatty acid monoethanolamide having 10 to 14 carbons in the acyl radical.

6. A process in accordance with claim 3 which contains a higher fatty acid isopropanolamide having 10 to 14 carbons in the acyl radical.

10 7. A process in accordance with claim 3 wherein said solubilizing agent is selected from the group consisting of the water-soluble soaps and organic sulfate and sulfonate detergents.

15 8. A clear aqueous liquid cosmetic composition comprising about 0.05 to 5% by weight of lanolin and a minor proportion of at least 0.25% by weight of a higher fatty acid alkylolamide having 8 to 18 carbons in the acyl group and up to 5 carbons in each alkylol group, the ratio of said alkylolamide to lanolin being at least 1:1 by weight, said lanolin and alkylolamide being dissolved in an aqueous liquid solvent medium having a water content of at least about 50% by weight of the total composition.

20 9. A clear aqueous liquid in accordance with claim 8 which contains a minor proportion of a water-soluble anionic organic surface-active agent dissolved in said aqueous solvent medium.

10. A clear aqueous liquid cosmetic composition comprising about 0.05 to 5% by weight of lanolin, about 25 0.25 to 20% by weight of a higher fatty acid alkylolamide having 10 to 14 carbons in the acyl group and up to 3 carbons in each alkylol group, the ratio of said alkylolamide to lanolin being from 2:1 to 100:1 by weight, and about 10 to 30% by weight of a water-soluble organic anionic detergent, said ingredients being dissolved in an aqueous solvent medium having a water content of at least about 60% by weight of the total composition.

25 11. A clear aqueous composition in accordance with claim 10 which contains a higher fatty acid monoalkylolamide having 10 to 14 carbons in the acyl group.

12. A clear aqueous composition in accordance with claim 10 which contains a member of the group consisting of water-soluble soaps, and organic sulfate and sulfonate detergents.

30 13. A clear aqueous composition in accordance with claim 10 which contains a higher fatty acid diethanolamide having 10 to 14 carbon atoms in the acyl radical.

35 14. A clear aqueous composition in accordance with claim 13 which contains water-soluble coconut fatty acid diethanolamide condensate.

40 15. A clear, transparent liquid cosmetic composition comprising about 0.05 to 5% by weight of lanolin and about 0.25 to 20% by weight of a higher fatty acid diethanolamide having about 10 to 14 carbon atoms in the acyl radical, the ratio of said diethanolamide to lanolin being from about 2:1 to 100:1 by weight, said ingredients being dissolved in an aqueous solvent medium having a water content of at least about 50% by weight of the entire composition.

45 16. A clear, transparent liquid shampoo composition comprising the following ingredients in the specified approximate amounts dissolved in an aqueous solvent medium having a water content of at least about 60% by weight of the composition:

Ingredients:	Percent
Lanolin	0.5
Liquid coconut diethanolamide	5
Water-soluble lauryl sulfate salt	9
Water-soluble dodecyl benzene sulfonate salt	8
Water-soluble higher fatty acid soap	2.5
